(57) **CLAIM**

I claim the ornamental design for a loopless belt, as shown and described.

DESCRIPTION

FIG. 1 is a perspective view of the loopless belt embodying the design of the present invention.

FIG. 2 is a front elevational view thereof;

FIG. 3 is a rear elevational view thereof;

FIG. 4 is a top plan view thereof;

FIG. 5 is a bottom plan view thereof;

FIG. 6 is an exploded left end view thereof; and,

FIG. 7 is an exploded right end view thereof.

1 Claim, 3 Drawing Sheets

FIG. 3.

FIG. 4.

FIG. 6
